UNITED STATES PATENT OFFICE.

ROBERT JAMES MANION, OF FORT WILLIAM, ONTARIO, CANADA.

RIFLE SIGHT GUARD.

Application filed July 23, 1924. Serial No. 727,655.

To all whom it may concern:

Be it known that I, ROBERT JAMES MANION, of the city of Fort William, in the Province of Ontario, Canada, a subject of the King of Great Britain, have invented certain new and useful Improvements in Rifle Sight Guards, of which the following is a specification.

This invention relates to protectors particularly adapted for the fore sights of rifles which are particularly liable to be damaged when rifles are stacked or stood in corners, and my object is to devise an efficient protector, which is easily applied, which adjusts itself automatically to different sights and different rifles, and which is easily carried in the pocket, if necessary, when not in use.

I attain my object by forming a cover of flexible material, preferably leather and preferably double. Between the parts of the cover I secure a stiffener, preferably of metal, and which is preferably of a V form, to fit over the sight so that the stiffened portion of the cover will rest on the rifle barrel. An elastic band is connected to the ends of the cover, which band is so proportioned that it is in tension when the device is slipped over a rifle barrel with the cover in position over the sight.

The invention is hereinafter more specifically described and is illustrated in the accompanying drawings in which—

Fig. 1 is a side elevation of the muzzle end of a rifle provided with my sight guard;

Fig. 2 a perspective view of the guard; and

Fig. 3 an end elevation of the guard, partly in section, in position on a rifle.

In the drawings like numerals of reference indicate corresponding parts in the different figures.

1 is the cover, which will vary somewhat in shape, depending on the rifle with which the device is to be used. In general, how-

ever, it will be of oblong form, tapering at its ends to which are connected the ends of an elastic band 2.

The cover is formed of any suitable flexible material, leather preferred, and is double, the parts being stitched together and preferably also cemented. Between the parts of the cover is positioned a stiffening member, preferably metal, and preferably also bent to a V form to fit over the rifle sight.

The device is slipped over the barrel of the rifle and the cover positioned directly over the sight as shown. The elastic band holds it securely in position.

What I claim is:

1. A rifle sight guard comprising a soft flexible cover adapted to fit over a sight and to engage the rifle barrel at each side of the sight; a stiffening member of V-shape incorporated in the part of the cover which bridges the sight and engages the barrel; and an elastic band connected to the ends of the cover and adapted to pass round the rifle to retain the cover in position on the sight.

2. A rifle sight guard comprising a double flexible cover adapted to fit over a sight; a stiffening member secured between the parts of the cover where the latter bridges the sight; and an elastic band connected to its ends adapted to pass round the rifle to retain the cover in position on the sight.

3. A rifle sight guard comprising a double flexible cover adapted to fit over a sight; a V-shaped stiffening member secured between the parts of the cover where the latter bridges the sight; and an elastic band connected to its ends adapted to pass round the rifle to retain the cover in position on the sight.

Signed at Ottawa, Canada, this 11th day of June, 1924.

ROBERT JAMES MANION.
